UNITED STATES PATENT OFFICE.

WILLIAM BARRY, OF OSWEGO, NEW YORK.

MAIL-DISTRIBUTING APPARATUS.

No. 908,195.

Specification of Letters Patent.

Patented Dec. 29, 1903.

Application filed December 30, 1902. Serial No. 599,632.

To all whom it may concern:

Be it known that I, WILLIAM BARRY, citizen of the United States, residing at Oswego, in the county of Oswego and State of New York, have invented certain new and useful Improvements in Mail-Distributing Apparatus; and I do hereby declare the following to be a full, clear, and exact description of the invention, such as will enable others skilled in the art to which it appertains to make and use the same.

This invention relates to mechanism for distributing mail matter, and the objects and nature of the invention will be readily understood and apparent from the following description of the construction set forth as one example out of many within the scope of this invention.

The invention comprises apparatus for receiving mail matter and the like from a common source and sorting the separate pieces and distributing the same to predetermined points of destination, such as boxes or receptacles.

In the accompanying drawings which merely illustrate one example out of many within the scope of my invention: Figure 1, is a partial vertical longitudinal sectional view of an apparatus for carrying out the object of my invention, one of the controlling levers being shown depressed and the letter conveyer or traveler being shown at an intermediate point in its path of movement. Fig. 2, is a side elevation of the apparatus of Fig. 1, looking at the opposite side thereof, the parts being shown in the same relative positions as in Fig. 1. Fig. 3, is a top plan view of the apparatus, the parts being shown in the same relative positions as in the foregoing figures. Fig. 4, is a detail sectional view, somewhat enlarged of the front portion of the machine, showing only the first row of the series of receptacles, a different key being shown depressed from that shown in the foregoing figures, and consequently a different box or receptacle being shown to receive the piece of mail matter, a different construction of letter guiding devices being shown in the box case. Fig. 5, is a vertical sectional view taken in the planes of the line 5—5, Fig. 2.

Fig. 6, is a sectional plan view taken on the line 6—6, Fig. 4. Fig. 7, is a vertical detailed view taken on the plane of the line 7—7, Fig. 4, all the levers however being shown in their normal positions. Fig. 8, is a cross section on line 8—8, Fig. 1. Fig. 9, is a detail top plan

of the actuating and ratchet mechanism beneath the case of boxes, the parts being shown in the position they assume after the dogs have been tripped and the mechanisms have started rotating. Fig. 10, is a detail perspective to more clearly illustrate how the lever slides operate on certain rock shafts. Fig. 11, is a detail perspective of the lower end of the swinging feeder arm showing the toe pivoted thereto and carrying needle points. Fig. 12, is a sectional view of the construction of Fig. 11, taken vertically through the toe.

It is the common practice in post-offices to distribute incoming and outgoing mail by hand according to the postal destination of each piece. The sorting boxes are arranged in cases, each case comprising a large number of boxes. Each box represents a certain postal route or destination, and all pieces of mail matter intended for a certain route or destination should be placed in the same box. As a box is filled the pieces therein are removed and secured in a bundle and labeled. The sorting or distributing clerks stand in front of the large cases and examine the address of each piece of mail matter to determine its postal route and then throw or place each piece in the box representing such route. This hand method is laborious, comparatively slow and is very apt to result in errors in sorting, and furthermore requires considerable floor space and numerous clerks. The mail matter is usually canceled, postmarked or back-stamped before distribution.

My invention contemplates the production of apparatus or mechanism comprising sorting or distributing devices under the control of the operator, for distributing or sorting the pieces of mail matter into predetermined boxes, receptacles or points of delivery, and wherein the apparatus can receive the pieces of mail matter at a common source and convey each piece therefrom to a particular receptacle or delivery point desired by the operator, in other words, to provide mechanism for sorting or distributing mail matter to take the place of hand distribution now in vogue.

Mail marking machines or devices are in common use, and if so desired mail marking or printing adjuncts can be used in connection with or as attachments to sorting or distributing apparatus, although such attachments are not essential in connection with distributing apparatus and can be employed

or dispensed with in each machine as desired. In some post offices the officials may prefer to employ the separate mail marking devices or machines there in use, for marking the mail before it is delivered to the distributing machine, while in other offices they may prefer to use marking devices as attachments to or in connection with the distributing machine.

Many and varied constructions and arrangements of sorting and distributing devices can be employed to carry out the objects and within the spirit and scope of my invention, as I believe that I am the first to produce apparatus for sorting and distributing mail matter.

In the specific construction shown in the drawings for the purpose of describing the broad conceptions and features of my invention, a tier or case of boxes or receptacles is shown. This case of receptacles is arranged vertically and supported and carried by a suitable frame work, such as *a*. The receptacles are arranged in horizontal rows forming vertical series, as the receptacles are parallel and arranged one above the other in vertical series, as well as one beside the other in horizontal series. Each box is arranged horizontally and closed, preferably, at one end, and open at the other so that the letters in each box can be secured together and removed in a bundle when desired.

The boxes, in the specific example illustrated, are arranged in series, and a letter way or passage is provided for each of said series, and the series of letter ways or passages open to or communicate with a general or main letter way or passage along which all the letters pass and from which each letter moves or is directed into the proper box or branch passage, from which the letter is directed into the proper box.

In the drawings, each vertical series of boxes is provided with its own letter passage or way arranged vertically beside the same, and each box has a longitudinal side opening. Thus in the example shown in Fig. 1, twenty three letter boxes or receptacles are shown and six vertical series of boxes, and six vertical letter passages or ways, each opening into the boxes of the particular series it feeds or supplies with letters. These letter ways are indicated by 1, 2, 3, 4, 5, 6, and the boxes of the first vertical series are indicated by *B'*, *C'*, *D'*; as they belong to passage way 1, and the remaining vertical series of boxes are correspondingly indicated by the same series of reference letters with the number indicating the particular letter passage ways belonging thereto, thus the second series of boxes are indicated by *A'*, *B'*, *C'* and *D'*.

In the specific example shown the general or main letter way or conveyer, 7, is formed on the arc of a circle above the boxes and at the top of the case, the floor thereof being sustained by the frame-work of the case, and

the upper ends of the vertical letter ways open through or terminate at said main way. The letters move along said main way on their flat faces and transversely thereof, and suitable gates, stops, or strippers are provided at the box or branch passages to direct the letter thereto or to prevent entrance of the letter thereto and permit its movement to some passage beyond. If desired, the floor of said main way can be formed by said gates, 1, 2, 3, 4, 5, and each gate can comprise a transverse rock or crank shaft 8, horizontally mounted in the frame work at one side of the upper end of the particular box or branch passage, and carrying a series of fingers extending laterally and forwardly therefrom in a direction opposite to that in which the letters move on the main way. These fingers of each gate are located a distance apart and normally lie about horizontally so that all of said fingers extend in the same direction, and the fingers of one gate rest on the shaft of the adjacent gate to the front and between the fingers thereof. The letters can easily slide or move over the floor of fingers thus formed which is without obstructions to the passage of the letters when all of the gates are in their normal positions. The upper ends of the box or branch passage are preferably curved about as shown, to tilt the letters so that the letters can easily slide thereinto, and assume a vertical position therein when the particular gate is elevated.

The letters enter said branch or box passage and drop down therein in a vertical position on edge. The lower ends of said ways 1, 2, 3, 4, 5, 6, are closed by curved deflectors or guides at the side openings of the bottom boxes *D'*, *D*, so that letters not entering the boxes above will always be directed into the bottom boxes which in the specific construction shown do not need gates. Also in the specific construction shown the last branch or box passage 6, of the series does not need a controlling gate but has a stop, stripper or guide 6', to direct all letters which have passed the length of the main way into said passage 6.

The box or branch passage have stops, or guides, or gates for each box, excepting the bottom boxes. These gates are preferably all alike, but are all indicated in the drawings by different reference characters to identify each gate with its particular passage and box, thus each gate is indicated by the number of its passage and the letter of its box, and hence the gates to all the "A" boxes are 2A, 3A, 4A, 5A, 6A, and the remaining box gates are indicated according to the same system.

Each box gate, deflector or guide, as shown 125 comprises a horizontal shaft 1^a, (or 2^a, 2^b, etc., according to the particular gate) mounted transversely of the case at the lower end of the narrow side slot into the box, with fingers extending up therefrom to close said opening 130

and normally rest out of the downward path of the letters in the passage, and having the lower curved or deflecting ends so that when the gate is rocked said fingers will extend across the way and catch the lower edge of the falling letter and deflect the letter from the way through the box opening, and said lower curved ends will guide the letter so that the same falls flat onto the bottom of the box or onto letters already therein. The opposite inner wall of each box can be provided with shoulders, corrugations, or catches 9, which will engage the opposite side edge of the letter and retard the same and hence tend to cause the letter to drop or fall with a flat face down and prevent the letter dropping within the box in a vertically or edge-wise position. However various arrangements of gates and boxes can be employed and the letters can fall free by gravity alone to each box or forcible or conveying controlling means can be employed as herein-after referred to and which as I am at present advised by experience might be broadly preferred. It will thus be observed that the main way gates direct each letter into a particular branch passage wherein gates determine the particular box that each letter enters.

30 As will be hereinafter pointed out, suitable means are provided whereby the proper gates are actuated to pass each letter into a particular and predetermined box. In the specific construction shown, each gate shaft 35 of the main way and branch passage gates has an extended end and provided with a crank and these cranks are operatively connected with certain operating and controlling means. The same system of reference characters is employed in indicating said crank arms. The main gate way crank arms are 1", 2", 3", 4", 5" and the branch passage gates are 1^b, 2^b, 3^b etc., or according to the particular passage and box. All of these cranks are preferably arranged at the back of the case of boxes as more clearly shown in Fig. 2.

35 The frame of the apparatus is extended forwardly from the box case and at the top extends downwardly and forwardly to form the main letter way beyond the said gates of said way and in the same arc or curvature as the remainder of said way. At the lower front end of the main ways a letter hopper, support or receptacle is provided for the bundle of mixed letters.

40 Various constructions and devices can be provided for this purpose if it be desired to provide a holder for the common pile or bundle of letters, though in the specific form shown in the drawings a support, table or floor 10, is provided on which the letters are piled with their addressed faces upwardly and their inner side edges resting against the lower portion of the floor of said main way.

This table is vertically movable and is maintained in a horizontal position, and is carried by the pair of parallel links 11, 11 at the upper front ends pivotally joined to a projection from said table and at their lower rear ends pivotally joined to the frame work so that as the follower moves upwardly it approximately follows the curvature of the main way. The said table is yieldingly pressed upwardly to constantly press or move the body of letters upwardly as their number decreases, by any suitable means such as a weight 12, connected with the table or a link by means of a cord passing over a pulley. It will be observed that the table can be pressed down at any time to receive a fresh bundle of letters.

The top letter of the bundle or pile is constantly pressed upwardly or against a suitable movable feeder arranged and constructed 85 to carry the topmost letter laterally from the pile at the will of the operator and when the proper operating devices are set in motion by the operator.

The specific feeder shown in the drawings 90 comprises a depending swinging arm 13, arranged above the pile of letters and at its upper end secured to the rock shaft 14, arranged transversely a distance above the main way and pile of letters and mounted 95 on rigid arms 15, extending from the frame work beyond the side edges of the main way. The lower free end of this swinging arm is provided with a swinging finger or toe 16, having its lower free end provided with several needle points rigid therewith. The toe and its needle points press down into engagement with the top most letter of the pile, and the toe is so inclined that the finger can swing outwardly without moving the letter 100 in that direction, the needle points sliding over the face of the letter, but so that when the finger is swung in the opposite direction the needle points will bite and grip the letter and lift and move the individual letter inwardly and upwardly from the pile and against the lower curved end of the guiding spring finger 17, and over the separating or retarding rib or obstruction 18, on the floor of the way.

110 The spring fingers 17, coöperate with the separator 18, in holding back the next letter and in preventing the passage of more than one letter at a time from the pile. Usually several feeder arms are employed and also 120 several spring fingers 17, can be used, as more clearly shown in Fig. 3. A spring finger 19, is preferably, provided to engage the outer edge portion of the top-most letter beneath the feeder and thereby hold the letters in 125 place and steady the letters of the pile and prevent the pile of letters tilting up at the outer edge. These spring fingers 17 and 19 can be adjustably and removably secured to cross bars between the uprights 20, rigid 130

with the frame work and arranged beyond the edges of the letter way.

21, is a horizontally disposed roll, which if desired can be used as an impression roll arranged transversely and within the floor of said main letter way at a point just above the pile of letters and is mounted on a shaft 22 journaled in the sides of the frame work just beneath the floor of said way.

10 23 is a roll which if desired can be used as a printing roll arranged above and co-operating with said impression roll and having its shaft mounted in the free ends of vertically swinging rock arms 24, at their upper ends 15 loosely mounted on or connected to the rigid uprights 20. The printing roll can thus move toward and from the impression roll and if desired a spring device can be employed to yieldingly hold the printing roll 20 toward the impression roll and to insure the proper impression on the letters.

Any suitable inking mechanism can be provided for the printing roll. The printing roll is formed with circumferential grooves. 25 permitting passage of the spring 17, and also to permit passage therethrough of the fingers of the letter conveyer hereinafter referred to, and the impression roll is also formed with registering grooves. The roll 30 23 can be provided with the usual printing characters and stamp canceling mark or dies, which it is not necessary to here show and can also be provided with a removable printing character, (not here shown) which 35 will impress on each letter the private mark of the particular operator to serve as a check in determining the person responsible for errors in the distribution of the mail matter.

25 is a drive shaft of the machine arranged 40 transversely in the lower part thereof and provided with beveled gearing 26, between said shaft 25 and the upright connecting shaft 27, mounted in suitable bearings in the frame work of the machine and at its 45 upper end connected with the impression roll shaft 22, by beveled gearing 28, so that the impression roll shaft is driven in the proper direction from said main shaft.

29 and 30 are gear wheels from the impression roll shaft to a driving gear 31, mounted on the same axis on which the arms 24, rock. The gear 31, meshes with and drives a gear 32 on the printing roll shaft. The printing roll is thus properly 55 rotated with respect to the impression roll irrespective of its vertical position as the gears 31 and 32 are constantly in mesh. The driving mechanism is so arranged that the power driven parts of the machine are 60 actuated only periodically and when a letter is presented for treatment and movement.

33 is the driving gear for the shaft 25. This gear runs loose on a rigid sleeve or bearing surrounding and concentric with 65 the drive shaft, and is driven continuously

through the medium of suitable gearing connected with the proper power. The gear is rigid with a ratchet wheel 34. A lateral arm 35, rigid with the normally inactive drive shaft 25, is arranged beside the ratchet wheel and at its outer end carries pivotally a dog 36 having a shouldered end to mesh with the ratchet teeth of said wheel 34. The opposite free end of the dog is curved and arranged to be normally engaged by suitable means holding the dog out of engagement with the ratchet wheel and hence maintaining the drive shaft out of gear with its driver. The dog is so formed or controlled that on release from 80 said stop its shouldered end will drop into engagement with the ratchet wheel and thereby throw the shaft into gear with the gear 33, and cause revolution of the parts together during a complete rotation when 85 the said rear end of the dog will be engaged and depressed by the stop and the dog released from the ratchet wheel leaving the dog in its normal position as shown in dotted lines in Fig. 4. The shaft 25 thus makes 90 one complete revolution at each operation and the gearing and shaft 27, therefrom to the rolls of the printing mechanism are arranged to also turn said rolls one complete revolution only at each operation, that is 95 whenever a key lever is depressed, as hereinafter mentioned.

The stop, or trip mechanism mentioned is shown in the drawings as a rock shaft 37 with an arm 42, having its lower free end 100 forming the stop which can be swung to release the dog and which then drops back to again catch, lift and hold the dog. The said rock shaft and trip are shown controlled by a lift rod 38, extending upwardly 105 at one side of the machine and at its upper end connected to control the feeder before described which carries each letter into the printing mechanism. The means specifically disclosed for this purpose comprise a bell crank 39 fulcrumed at its angle to the frame arm 15, with the lift rod 38, pivotally joined to its laterally extending arm and having its upwardly extending arm arranged to swing out the feeder arms to catch and 115 feed forward a letter when said lift rod is moved up to throw the drive shaft in gear and thereby cause rotation of the printing rolls. The said upper free end of the lever 39, is here shown engaging a lateral arm 40, 120 depending and rigid with the rock shaft carrying the swinging feeders, to swing said arm 40 outwardly and thereby carry the feeders outwardly to grasp the letters as before described.

125 A device is provided, as hereinbefore described, which lifts said rod 38 and then trips, whereupon the rod is returned to its normal position and the feeder is swung inwardly to carry a letter into the printing

mechanism, by a suitable spring mechanism, such for instance as one or more springs 41, coiled on the rock shaft 14 carrying the feeder and constantly tending to hold the feeders at their limit of inward movement toward the printing mechanism. A suitable stop or stops can be provided to limit the movement of the parts under action of said spring device. For instance, I show a rigid stop 37, to limit the downward movement of the arm or trip controlling the dog 38, see Fig. 4:

Any suitable mechanism or device is provided to move carry or propel the individual letters along the main letter way so that they can be switched off into the proper branch or box letter passages. As an example of a device which might be employed for this purpose, although my invention is not limited to any particular means for or method of moving, carrying, or directing the letters to passages communicating with certain boxes, I show a swinging arm 43, arranged at one side of the machine and fulcrumed at bearing 44, which is approximately the center from which the arc or circle of the main letter way is struck. This arm extends to a point above the plane of the main letter way. This swinging arm 43 is provided with a horizontal rod 44', extending laterally therefrom transversely of and a distance above the floor of the main letter way. Several yielding fingers 45, extend downwardly and forwardly from said rod 44 and are formed with the downwardly projecting shoulders or catches 46, and with beveled or inclined outer faces, so that said fingers form what might be termed a letter conveyer or propelling rake and thus the lever 43 can swing so that rake arms or fingers 45 will extend through the grooves in the rollers of the printing mechanism, permitting the shoulders of said fingers to catch behind the front edge of the letter in said rolls and hence when the movement of the lever 43 is reversed the letter will be drawn or pushed over the way. These fingers 45 are arranged to move between the fingers forming the floor of the main letter way so that when any one of the gates of the main letter way are swung up the letter will be thereby stripped from said fingers 45, and directed down into a letter passage. These fingers 45 are yielding and are held down so as to insure proper movement of the letters thereby, yet so that the shouldered or catch ends or portions of said fingers 45 will not injuriously engage any portion of the main letter way. The fingers usually turn on rod 44', and are held down by springs, and their downward movement is limited by stops. This letter rake or conveyer can be guided and steered in its movements by a lateral arm 47 rigid with the lever 43, and carrying loose grooved wheel 48, straddling and traveling on a track rail

49 arranged longitudinally to one side of the main letter way. This letter feeder or conveyer is normally inactive. Various mechanisms can be employed to periodically actuate the same at the proper moments with respect to the other mechanisms which act on each letter.

In the specific constructions shown in the drawings the normally inactive shaft 25 is provided with the rigid crank arm 50 having its outer end pivotally connected by a pitman 51, with the lever 43 to one side of the fulcrum thereof. It will thus be noted that one complete revolution of the shaft 25, will move the letter feeder or conveyer the length of the main letter way twice. The normal position of the letter feeder or conveyer is at its limit of movement at the rear end of the main letter way. When the key lever or controlling mechanism, to be hereinafter referred to is depressed the lift rod hereinbefore described throws the shaft 25 into gear with its power and sets the feeding and printing mechanism into action. A letter is thereby carried into the printing mechanism. At the same time the crank 50 begins to move thereby moving the letter conveyer forward above the main feed way until the fingers 45, extend through the printing mechanism and catch the letter whereupon the letter feeder moves in the opposite direction carrying the letter toward the rear end of the way. For instance in Fig. 1, the feeder is shown almost to its normal position after depositing a letter in letter passage 4, intended for box C. The letter is deposited in its proper passage and the feeder returns to rest at its normal position at the rear end of the way. It will be observed that each time the shaft 25, is thrown into gear with its driving means a complete revolution is made before the shaft is again thrown out of gear so that a full feeding stroke of the letter conveyer is insured at each operation.

Various arrangements of controlling and actuating mechanisms can be employed to set the various devices in action to carry forward each letter, and to set various gates to deposit each letter, taken from the common pile or from a common source in a particular box or receptacle of a series. In the specific example shown in the drawing, a key is provided for each box or receptacle. The bank of keys is composed of series of keys in number equal to the number of boxes or receptacles, and each key is provided with characters or printed matter the same as, or indicating its particular box. Thus in following out the system of indicating characters adopted, the twenty three keys corresponding to the twenty three receptacles shown, are, respectively, indicated by the same indicating characters. Thus the keys are indicated by B', C', D', A', B', C', D', etc., which also indicate the boxes. The bank of keys

is usually arranged in steps and is preferably located beyond the front end of the machine beneath and projecting outwardly beyond the plane of the common pile of mixed letters 5 so that the operator can sit or stand in front of the machine and look down on the keys and also look down on the top-most letter of the said pile and thereby easily and quickly read, the address of the top-most letter and 10 then depress the key corresponding to the box in which said letter belongs. It should be noted that the keys and top-most letter of the pile are within the field of vision or view of the operator so that he can almost simultaneously see the address and proper key. All of the key levers are preferably mounted 15 at their inner or rear ends loosely on a shaft 52 extending transversely of the front of the machine and between and secured to the forwardly projecting side frames thereof. All the levers extend horizontally and forwardly from their fulcrum points in approximately the same plane, with their front ends bent upwardly and carrying the keys which are 20 provided with the indicating characters as before described.

The frame sides are provided with rigid forwardly extending arms 54, arranged above the key levers 53 and connected by transverse rail 55, also arranged above all of the key levers and limiting their upward movement, and carrying vertical separating and guiding plates 55', between the key levers.

56 is a vertical swinging bail having vertical upwardly extending ends beyond the series of key levers and at their upper portions pivoted to the arms 54. This bail extends beneath all of the key levers and has the beveled upper edge 57. The bail is usually 30 maintained in its normal upright position by suitable means, such as springs secured to its extended upper ends. Each key lever has a downward projection 58 above the beveled edge of the bail and each projection has an 35 inclined face terminating in an upwardly facing shoulder 59, leaving ample space between the shoulder and the lower edge of the key lever to receive the bail 56. The arrangement is such, that when a key lever is 40 depressed the beveled projection 58 on the beginning of the downward movement engages the beveled edge of the bail and thereby swings the bail to one side and permits it to swing back over the short shoulder 59 of 45 the projection, thereby locking the key lever in its depressed position while the bail limits the downward movement of the key lever. The key is thus held depressed or 50 locked until another key is depressed, when 55 the same operation is repeated and the locked key is released and allowed to return to its normal position under the impulse of a spring and before the lever being depressed has moved but a slight distance.

55 The key levers are yieldingly held up to

their normal position by suitable springs, such as springs 60 secured to the frame with their upwardly springing free ends engaging the under edges of the key levers. Each key lever is provided with a slide 61, operated thereby. The vertical series of separate slides 61 are shown vertically arranged at the front portion of the machine, each with its lower end pivotally joined to its key lever at a point to one side of the fulcrum 70 thereof. The upper ends of the slides are all preferably longitudinally slotted, as shown more clearly in Fig. 4, and a transverse rod 62 is passed loosely through said slots of all the slides. This rod 62 is at its 75 ends secured to the forward ends of lateral arms 63 extending forwardly from and rigid with a rock shaft 64 at its ends mounted in the frame sides and extending transversely thereof. This rock shaft 64, is provided 80 with a rearwardly extending trip arm 65 terminating adjacent the lift rod 38 hereinbefore described. The lift rod 38 is provided with a swinging trip or catch 38', normally arranged with its lower end above and resting on the rear end of the arm 65 and so that when the arm 65 moves up it will lift the rod 38 through the medium of said catch 38' and will then slip past the catch 38' and release the rod 38. The catch 38' is so arranged 85 that the arm 65 can return to its normal position by pressing the catch to one side, the catch then springing out over said arm. 90

When any key lever is depressed the slide plate 61 thereof is drawn down thereby drawing down the rod 62 and operating the lift rod 38. It should be noted that the elongated slots in the upper ends of the slides 61 permit downward movement of the rod 62 under the impulse of one slide without thereby causing downward movement of all the other slides, and said rod also forms a guide for the slides. Each slide 61, is designed to operate or control mechanism which will direct the letter when its key is depressed to the particular box corresponding to and indicated by said key. Various mechanisms can be provided for this purpose. Each key controls a main letter way gate and also a box passage gate, except that the keys corresponding to the "D" boxes do not operate box or passage gates, and the keys corresponding to boxes A⁶, B⁶, C⁶, D⁶, do not actuate a main way gate. The reason for this is apparent, as no gates are required for the boxes of the bottom row, nor for the last box or branch passage from the main way. It might be also noted that the key D⁶, corresponding to box D⁶, operates no gates at all, but merely sets the power driven mechanisms to work. However my invention is not limited in these respects as other arrangements of boxes or letter moving and controlling mechanisms might require other arrangements of gates or even dispense with 110

gates, as my invention is not limited to the employment of such, although I prefer them as at present advised from practical tests.

In the drawings, the specific means disclosed for controlling the gates comprises a vertical series of transverse rock shafts C, B, A, 5^a, 4^a, 3^a, 2^a, 1^a. The rock shafts are mounted at their ends in the sides of the frame, and are preferably all located in a vertical plane parallel with and close to the plane of the vertical slides 61, and yet so that each rock shaft extends transversely of all the slides. At the side of the machine, each rock shaft has a crank arm connected by a suitable wire or other connection with certain of the gate cranks and said connections are shown clearly in Fig. 2, arranged at the back of the box case. I prefer in the arrangement of boxes shown to connect the box or passage gate cranks together in horizontal series as shown in Fig. 2, so that all the A, B, or C, box gates will open and close together. This can be done without interfering with the proper placing of the letters, as only one letter is in a passage at a time. The crank 1^a of rock shaft 1^a, is connected by a wire or the like to crank 1^b of gate 1^a, and crank 2^a, of rock shaft 2^a, to crank 2^b, of gate 2^a, and crank 3^a, of rock shaft 3^a, to crank 3^b, of gate 3^a, and crank 4^a, of rock shaft 4^a, to crank 4^b, of gate 4^a, and crank 5^a, of rock shaft 5^a, to crank 5^b, of gate 5^a. It will thus be observed that these five rock shafts just mentioned control the five main letter way gates. The other three rock shafts are, respectively, connected to control the gates of the rows of A, B, and C, boxes. Thus the crank A^a, of rock shaft A, connects to the series of cranks 2^a, 3^a, 4^a, 5^a, 6^a. Thus the rock shaft A, controls the gates of the A, boxes and must be actuated by each of the five keys corresponding to said boxes. The crank B^a, of the rock shaft B, in the same way connects with the six cranks of the gates of the B, boxes, viz: 1^b, 2^b, 3^b, 4^b, 5^b, 6^b, and hence each one of the six keys corresponding to said B, boxes must actuate the rock shaft B. The crank C^a, of the rock shaft C, connects with the series of cranks, 1^a, 2^a, 3^a, 4^a, 5^a, 6^a, of the gates of the C, boxes and rock shaft C, is actuated by all the keys corresponding to the C, boxes.

Various means can be employed to cause the slides of the key levers to operate certain rock shafts without operating the remaining rock shafts. This can be conveniently done by series of differently arranged projections. Thus the rock shafts are formed with flanges or arms 67, rigid therewith and projecting toward the slides 61, and normally about horizontal. The edges of said flanges are slotted or notched to receive the respective slides. Each slide has a cross pin 68, passed therethrough and arranged on the flange or arm of the rock shaft which it is to operate.

Hence when the slide is forced down it slides through the flanges or arms which it does not operate but the pin or pins 68 thereof depress the flange or flanges which it should operate and hence rocks the shaft or shafts thereof and opens the proper gates.

All of the slides connected with the keys representing the boxes, excepting the bottom and end rows, have two pins to operate two rock shafts and hence open the proper main way gate and branch passage gate. Hence one of said slides has one pin to depress one of the upper five flanges or arms 61, which actuate main way gates, and also a pin to operate one of the lower three flanges to actuate the proper box gate. The slides connected with keys corresponding to the bottom boxes (excepting box D^a) have only one pin 68, each to operate on one of the upper five flanges which control main way gates. The slide connected with the key corresponding to box D^a, has no pins, as no gates are actuated thereby. The slides connected with the keys corresponding to boxes A^a, B^a, C^a, have only one pin 68, each operating on the three lower flanges, respectively, which actuate the box gates.

It will be noted that the initial feeder is normally held at its limit of inward movement by the spring 41, shown particularly in Fig. 5, and that when a key lever is depressed the rod 38 is lifted thereby swinging the initial feeder outwardly against the tension of spring 41 until the arm 65, slips past the trip 38', whereupon the feed stroke actuating spring 41 moves the initial feeder inwardly on its letter feeding stroke. The feeder is hence yieldingly driven on its letter feeding stroke, by the swing, whereby the feeder can yield or even stop at any point in its feeding stroke according to the resistance offered by the letter, thereby reducing to the minimum the danger of mail matter being mutilated by the feeder should the pieces of mail matter wedge or refuse to enter the feed rolls. The act of depressing a key lever, or the depressing movement of the key lever under the action of the operator's hand or finger moves or forces the initial feeder on its return stroke, while the feed stroke spring 41, moves the feeder on its feeding stroke.

As I am at present advised by practical experience, it is preferable to provide means for forcibly guiding and possibly moving or assisting the letters in the branch or box passages. In Fig. 1, the boxes are shown with their inner sides, open almost entirely, and with the gates as before described having their rock shafts at the bottoms of the side openings. The gate fingers are constructed and arranged so that they can, when open, rest against the opposite wall of the passage and thus form a gradual incline across the passage to the box whereby the letters will engage the same in an upright position and

be guided into the box in an upright position and crowd over the other letters therein, and thus drop with their lower edges on the bottom of the box. Light coiled expansive 5 springs 70, can be located in the boxes to yieldingly hold the letters upright and to be compressed as the box fills.

Traveling belts 71, or other means can be arranged longitudinally of each branch or 10 box passage and curved light springs or spring fingers 72 are shown to press the letters against said downwardly traveling belts. These belts assist the letters and maintain them in the proper upright position and 15 against tilting or wedging, which might otherwise occur if a letter contained a heavy article in one end, or under some other conditions. These belts also assist in forcing the letters into the boxes. A series of separate 20 belts or plies are arranged in each passage alternating with the gate fingers which swing out between the belts.

Various arrangements of belts and operating means therefor can be provided. Thus 25 in Fig. 1, spring rollers 73 are mounted transversely at the upper ends of the letter passages. The belts of each passage are secured to and wound on the roller at the upper end thereof and the springs within the rollers are 30 arranged to constantly tend to wind up the belts thereon and thus move the belts up in the passages. Idler pulleys 74, are mounted at the lower ends of the letter passages, and the belts of all the passages are carried rear- 35 wardly over said pulleys, and secured together at their ends and provided with a single pulling cable or connection 75, extending forwardly beneath the case. A pulley 76, at the rear of the case is provided for said con- 40 nection or the belts secured thereto. The cable 75 is secured to winding drum 77, loose on countershaft 78, mounted beneath the case. A ratchet wheel 79, is rigid with said drum. 80 is the main drive shaft of the 45 machine having a gear 81, meshing with gear 82, loose on shaft 78 and which meshes with and drives gear 33, loose on shaft 25.

The gear 82, has a ratchet wheel 83 rigid therewith, the teeth of which are arranged 50 oppositely to those of ratchet wheel 79, rigid with the drum. A ratchet arm 83', is loose on the shaft 78, between the two ratchet wheels, and carries two oppositely arranged dogs 84, 85, for said two ratchet 55 wheels, respectively. The two dogs are normally held with their catch ends out of engagement with their ratchet wheels by a single trip 86, engaging the extended rear ends of both dogs or parts rigid with said 60 ends. This trip 86, is a swinging finger depending from the frame and connected pivotally by a push rod 87, with another swinging arm 88, so that the two arms will 65 constantly tend to swing back to their normal vertical positions with arm or trip 86,

holding up the dogs. If desired a spring can be provided to return said arms and a stop acting against the spring, see Fig. 1. The rod 87, has a projection 87', in the path of a projection 87", on the crank arm operated 70 by ratchet wheel 34. It will thus be observed that when the key is depressed and the movable parts of the machine are set in operation thereby that the pin 87", engages pin 87', and thereby moves rod 87, endwise 75 and swings trip 86, from the two dogs held thereby. The catch ends of these dogs then drop into their respective ratchet wheels and hence the arm 83', is swung with the gear 82, and thereby carries around the drum and 80 winds up the cable 75, thereon, and hence rapidly pulls down all the belts in the various passages, and starts this operation before a letter could possibly enter any of said passages. The said belts continue to 85 move down a short space of time after the main way feeder has passed the last opening to the end passage 6, so as to carry a letter which might be in said passage to the last 90 box thereof. This is accomplished and 95 possible because the pins 87' and 87" do not engage and, consequently the two dogs 84, 85, are not tripped until a short space of time after the shaft 25, operating the feeder lever 43, has been thrown in gear, and as the drum and parts connected therewith make a complete revolution before the trip 86, again engages and rides upon the extended 100 ends of the two dogs and raises their catch ends from the ratchet wheels and thus throws 105 the drum out of gear. The continued movement of the belts is also attained by reason of the fact that gear 82, actuating the winding drum is of greater diameter than gear 33, directly driving the shaft actuating 110 the main letter way conveyer. As soon as released the drum rebounds under the impulse of the spring rollers which thereby return the belts to their normal positions wound on the spring rollers. When the 115 drum rebounds the dog thereof, is held elevated by the trip. It should be noted that in this specific construction the drum makes but one complete rotation whether winding or unwinding.

As has been hereinbefore stated various means can be provided to carry the letters successively from the common source or pile to passages or various boxes and the term which I employ of main letter way or conveyer is indicated to broadly or generically describe any such arrangement and it might also be noted that the branch or box passage can supply or communicate with one or more boxes.

Spring devices are usually employed to return the box gates to their normal positions, and to hold the same yieldingly closed, as shown in Fig. 2. As the main way gates swing up in opening, gravity is usually suffi- 130

cient to close them, although spring devices can be employed if desirable. Springs are preferably provided for the various dogs 35, 84 and 85 to render them quick in action. 5 In Fig. 4, the spring for dog 36, is indicated by 36'.

As examples of devices which can be employed for moving the pieces of mail matter to their various points of destination, during 10 the sorting process, I show arrangements of oscillatory or reciprocatory letter moving devices and feed belts although I do not thereby wish to limit the broad features of my invention to any particular construction for or 15 method of moving, carrying or directing the pieces of mail matter from a common source to various boxes or other receptacles, or to passages communicating with boxes or points of delivery. Within the broad features 20 of my invention, intermittently movable letter moving or propelling devices need not be employed, nor, under said broad features is it necessary to employ clutch or make and break mechanism, nor an initial 25 feeder. In fact, any suitable letter feeding devices, such as commonly employed in mail marking machines, might be used for initial feeding. Again, it is not necessary under the broad features of my invention, that a 30 support for the common pile of letters be employed to successively display the addressed face of each letter to the view of the operator.

Any suitable mechanism can be employed 35 to convey the letters successively or otherwise from the common source to various passages or to various receptacles or boxes, and the term I employ of "main letter way" or "conveyer" is intended to broadly or 40 generically indicate any such arrangement, and it might also be noted that the branch or box passages or ways might each supply or communicate with one or more boxes or receptacles, and many other arrangements and 45 constructions might be employed as I believe myself to be the first to produce a device, whatever its construction, for distributing mail matter, and, as at present advised, intend that all constructions for accomplishing such purpose shall fall within the spirit 50 and scope of my invention, whether or not a general way or conveyer be employed from which the letters are distributed, or whether or not branch ways or conveyers be employed.

It should be noted that the term "letters" employed herein refers generally to mail matter of any sort, kind or condition which any apparatus, within the spirit and scope of 60 my invention, is adapted to receive and handle. It should also be noted that various mechanisms can be added to the apparatus illustrated, or can be taken from the apparatus illustrated without departing from the spirit and scope of my invention, which

broadly contemplates, among other features, an apparatus for taking mail matter from a common source and distributing the same to various predetermined points.

The invention is not limited to a case or 70 series of boxes, as the letters can be delivered to various predetermined points or locations, whether such various locations be in the form of compartments, receptacles, boxes, repositories or holders for the letters or otherwise. 75

If so desired the arrangement shown in Fig. 11, can be provided with any suitable means in the boxes to hold the letters together and upright, such as springs shown in dotted lines in some of the boxes, or as 80 shown in full lines in Fig. 1. If desired the letter moving devices of Fig. 11, can deposit the letters flat face down or horizontally in the boxes.

For the sake of making clear the broad 85 features of invention involved in this case, I have specifically described details of construction in the examples shown, but my invention is not thereby limited, and I do not wish to limit myself to such examples as 90 shown but consider myself broadly entitled to all other structures falling within the spirit and scope of my invention, as I believe myself to be the first to produce an apparatus for sorting or distributing mail matter 95 and broadly claim apparatus for attaining such object.

What I claim is:—

1. In an apparatus of the character described, a case or series of boxes having letter 100 receiving openings thereinto, in combination with a main letter way or conveyer arranged above the case of boxes and arranged to discharge letters thereto, means for individually distributing the mail matter and mail 105 marking mechanism arranged to deliver the letters separately to said main letter way, substantially as described.

2. In combination, series of boxes or receptacles, mail matter individual sorting and 110 moving means, and gates, deflectors, or strippers controlling the letters and directing each individual piece of matter on its particular course, substantially as described.

3. In combination, a letter way, an upwardly moving support arranged to carry a pile of faced up mail matter and to display the addressed face of the letters successively to the view of the operator, a feeder arranged to successively remove the letters from the 115 top of the pile and pass the same on toward said way, means for individually distributing the letters, and letter conveying mechanism, substantially as described.

4. In combination, an upwardly pressing 125 support, an initial swinging feeder to successively move the topmost letters therefrom, a printing mechanism receiving said letters, and a conveyer or letter mover receiving the letters from said printing mech- 130

- anism, and mechanism for periodically actuating said feeder and printing mechanism together, substantially as described.
5. In an apparatus of the character described, a holder for the common pile of mixed mail matter, an initial feeder to successively remove letters therefrom, a printing mechanism, a main way letter feeder or conveyer, letter boxes having branch passageways from said way, letter directing or guiding means, a series of key levers indicating and corresponding to the boxes and connected with and controlling said directing means, actuating mechanism, and connecting devices controlled by said key levers, whereby the initial feeder and the printing mechanism are operatively coupled with the actuating means whenever a key lever is depressed.
- 20 6. In combination, a frame, a vertically movable horizontally disposed table provided with means yieldingly pressing or moving the same upwardly, a rigid wall extending up beside and above the table 25 against which the edges of letters on the table can aline, and a feeder to take the letters successively from the pile, and individual letter distributing and directing mechanisms, substantially as described.
- 30 7. In combination, a vertically movable horizontally disposed holder arranged to receive a pile of mixed letters and constructed to successively expose the addressed face of each letter to the view of the operator, 35 means yieldingly pressing said holder upwardly, and feeding mechanism successively removing the letters therefrom, and individual letter distributing and directing mechanisms, substantially as described.
- 40 8. In combination, a holder arranged to receive the pieces of mail matter, and means to move the holder, a spring exerting downward pressure on the letters in the holder, a feeder successively taking the letters from 45 the holder, and individual letter distributing and directing mechanisms, substantially as described.
- 50 9. In combination, a movable holder arranged to constantly press and move a pile 55 of letters, swinging arms connected to said holder to move and maintain the holder in planes parallel with each other, means for yieldingly moving said parts to feed the pile of letters, an initial feeder, and letter moving and directing devices for distributing the letters to various predetermined points, substantially as described.
- 60 10. In combination, a side guide or wall against which the edges of a pile of letters can be alined, a holder and mover for the pile of letters, a curved spring resting on the outer portions of the end letter to hold the pile, a feeder to remove the letters successively from beneath said spring, a letter marker to which said feeder successively de-
- livers the letters, letter moving means taking the letters from said marker, and directing and controlling means for delivering the letters at various predetermined points, substantially as described. 70
11. In combination, means to receive and hold the letters, a wall or guide along which the letters are moved therefrom, a separator on said guide, a curved guiding spring opposite the letters and pressing toward the separator, a feeder to carry the letters against said spring and over or past the separator, a letter marker to which said feeder successively delivers the letters, letter moving means taking the letters from said marker, and directing and controlling means for delivering the letters at various predetermined points, substantially as described. 75
12. The feeder comprising a swinging arm at its free end carrying a pivoted toe provided with sharp points, a letter marker to which said feeder successively delivers the letters, letter moving means taking the letters from said marker, and directing and controlling means for delivering the letters at various predetermined points, substantially as described. 80
13. The feeder comprising a depending swinging arm arranged above the letters with the pivoted toe on its lower end having sharp points to partially lift the letter and move the same laterally, a letter marker to which said feeder successively delivers the letters, letter moving means taking the letters from said marker, and directing and controlling means for delivering the letters at various predetermined points, substantially as described. 85
14. Means to hold and press up the letters, and a feeder arranged above the same and constructed to partially lift and move the topmost letters laterally and successively from the pile, a guiding spring for the inner end of each letter being fed, a letter marker to which said feeder successively delivers the letters, letter moving means taking the letters from said marker, and directing and controlling means for delivering the letters at various predetermined points substantially as described. 90
15. A feeder comprising a movable carrier provided with a swinging toe at one end pivoted to the carrier so that its free end can swing toward and from the face of the letter to be moved, said free end of the toe having a letter gripping surface, said toe arranged at an angle to the flat face of the letter to be moved, and arranged to grip and move the letter when the carrier is moved in one direction and to slide freely over the face of a letter when the carrier is moved in the opposite direction, substantially as described. 95
16. Mechanism for receiving and feeding a pile of mail matter or sheets upwardly, in combination with a swinging carrier mov-

able back and forth above the topmost piece on said pile, a vertically swinging toe pivoted to said carrier and at its free end provided with a letter gripping edge arranged at an angle to and resting on the top-most sheet, and a stop limiting the downward swing of said toe and permitting free upward swing thereof, substantially as described.

17. Mechanism for supporting and moving up a pile of letters and means for individually distributing said letters in combination with a swinging arm arranged over the pile, a spring device for moving the arm in one direction, the actuating means comprising a trip mechanism to move the arm against the spring and then release the same and permit quick movement thereof under the impulse of the spring, and a feeding device carried by the free end of the arm, substantially as described.

18. Mechanism for carrying and moving a body of letters and means for individually marking and distributing said letters in combination with the feeder arranged to carry the letters successively and laterally from the pile, spring mechanism actuating said feeder in one direction, positively actuating mechanism for moving the feeder in the opposite direction and a tripping device to release the feeder from the actuating mechanism and permit the quick feeding stroke under the action of the spring mechanism.

19. In combination a main letter way, a letter marking mechanism comprising rollers at said way, the letter feeding device over the way to carry the letters to the printing mechanism, and a main feeder to carry the letters along the way from the printing mechanism and to discharge the letters at various points along the way, substantially as described.

20. A main letter way, means at one end thereof to support a body of letters, supports extending up from the way, an initial feeder carried by such supports, a printing roller above the way, and a main letter mover operating over the way and discharging the letters at various points therefrom, substantially as described.

21. A mail distributing apparatus, where in the letters are successively moved from a common source and delivered to various predetermined points or receptacles, comprising in combination a main way, means for individually distributing or sorting letters or mail matter, a printing mechanism having circumferential recesses or depressions and a letter mover arranged to extend into said recesses and receive each letter from the printing mechanism, substantially as described.

22. In an apparatus of the character described, a main way from which the letters are discharged at various points in combination with the letter moving rake reciprocating

ing back and forth the length of the way, substantially as described.

23. In combination, in a mail distributing apparatus means for individually sorting the letters or mail matter a floor or way having a depending end portion, a letter holder at the lower end thereof, an initial letter feeder, a printing mechanism on the way, the way extending directly rearwardly from the printing mechanism, substantially as described.

24. A mail distributing apparatus comprising, letter conveying and guiding mechanisms, controlling means therefor, a letter floor, and means whereby the addressed face of each piece of mail matter is disclosed to the operator in combination with supports extending up therefrom, a printing mechanism comprising one roll in the floor of the way and the other co-acting roll above the same, and provided with movable carriers confined to said supports, and positive driving means for both rolls, substantially as described.

25. In a mail distributing apparatus, the combination of a case of letter receptacles having passages thereto, a main letter way communicating with all of said passages, a swinging arm carrying a letter mover traveling over said way, and letter controlling and actuating mechanism, substantially as described.

26. In a mail distributing apparatus, the combination of a series of letter receptacles, a curved main letter way above the same and communicating with the various receptacles, an oscillating arm swinging from a center and carrying a letter conveyor movable along said way, controlling means and actuating devices, substantially as described.

27. The combination of means for individually distributing mail matter, a letter feeder comprising a transverse rod having laterally projecting fingers with catch or shouldered ends, an oscillating arm carrying the same and actuating mechanism, substantially as described.

28. A floor or way, in combination with a feeder comprising a head provided with operating means and arranged transversely of said floor with yielding letter engaging and moving fingers projecting therefrom to slide the letter along the floor, series of letter receptacles communicating with said way, letter guiding means, and controlling mechanisms, substantially as described.

29. A curved letter way or floor, in combination with a swinging arm extending up beside the floor and at its free end carrying a letter mover to convey the letters along the way, series of letter receptacles beneath and communicating with said way, guiding and controlling mechanisms, substantially as described.

30. A case or series of boxes, letter passages communicating with the boxes, a main

letter way communicating with the passages, a mail marking mechanism and gates between the passages and way forming the floor of the way, substantially as described.

31. Series of boxes, letter passages communicating therewith, swinging gates normally closing certain boxes and arranged to direct letters thereinto when opened, a mail marking mechanism a letter conveyer arranged to discharge each letter into any particular passage, and controlling means, substantially as described.

32. A case or series of letter receiving boxes or receptacles, letter passages communicating with the boxes, swinging gates at the receiving ends of the passages, a mail marking device and a letter mover or conveyer common to all said passages and so formed that any gate can swing out through the same and deflect the letter therefrom into the particular passage, substantially as described.

33. The vertical series of boxes, each series having its own vertical letter passage, means in each passage to direct a letter into any particular box, and prevent entrance of the same into other boxes, mechanism for delivering each letter into a particular passage and preventing entrance thereof into other passages, letter moving and marking mechanisms and controlling devices, substantially as described.

34. In combination, normally inactive mail marking mechanism, a normally inactive feeder for supplying letters successively thereto, driving means, actuating mechanism for moving the feeder one feeding stroke and driving the printing mechanism, and a key lever connected to throw the actuating mechanism into gear with said driving means, substantially as described.

35. In a machine of the character described, series of boxes or receptacles, letter moving and directing devices arranged to deliver each letter into any particular box, a normally inactive mail marker, a normally inactive letter conveyer, series of key levers, corresponding to said boxes and controlling said letter directing devices each lever arranged to throw said normally inactive parts into gear with driving means, substantially as described.

36. Series of boxes having a passage communicating therewith, letter forcing belts longitudinally of the passage and spring fingers coöperating with the belts, substantially as described.

37. In an apparatus of the character described, several series of boxes, letter passages for the series, respectively, each passage opening into boxes of the series, reciprocating letter forcing belts in each passage, driving means, all the belts connected with the driving means and actuated to-

gether longitudinally of the passage, substantially as described.

38. In an apparatus of the character described, series of boxes, series of letter controlling guides or gates, series of crank shafts having connections to various gates and series of key levers, certain key levers connected to actuate certain crank shafts, and a trip mechanism controlled by all the key levers substantially as described.

39. In an apparatus of the character described, normally inactive letter feeding and mail marking mechanisms, driving means, mechanisms to connect the driving means with said normally inactive mechanisms, series of boxes, series of letter directing gates or guides and series of key levers, all said levers connected to actuate said mechanism to operate said normally inactive parts and certain of said key levers connected to actuate certain of said gates, substantially as described.

40. The combination of series of slides or plates, series of separate manually operated devices, such as key levers, each connected to a slide, so that each key lever operates a particular slide, boxes, series of letter directing means, certain slides controlling and actuating certain letter directing means, periodically operating letter moving devices, and means whereby said slides throw said letter moving devices into and out of operation substantially as described.

41. In an apparatus of the character described, series of mail receptacles, a series of manually operated slides corresponding thereto, letter directing means each slide controlling said means to direct the letter to a particular box, actuating mechanism, driving means, trip mechanism normally holding said actuating mechanism out of gear, each slide connected to operate said trip to throw the actuating mechanism in gear with said driving means, substantially as described.

42. In an apparatus of the character described, series of letter directing means, a series of rock shafts, each rock shaft controlling certain letter directing means, actuating means, a trip mechanism and series of keys, each key arranged to rock a certain shaft or shafts, the remaining shafts remaining inactive, substantially as described.

43. In an apparatus of the character described, a series of rock shafts having cranks, a series of manually operated slides, said slides having means to engage and rock certain shaft or shafts and move independently of the remaining shafts, and a trip mechanism actuated by each slide substantially as described.

44. Letter moving mechanism, a driver, trip mechanism normally holding said letter moving mechanism out of gear with said

- driver, a rock shaft for releasing said trip; and a series of keys all independently acting on said rock shaft, substantially as described.
45. In combination, a series of crank shafts, each having a forwardly extending flange or plate, the series of slides arranged loosely in openings in the plates, said slides having projections to strike certain plates only, a trip mechanism actuated by each slide and means for longitudinally moving the slides, substantially as described.
46. A series of boxes, each having a side letter inlet opening and a guide and means to discharge a letter edgewise into said opening so that it falls flat face down in the box, means for individually sorting pieces of mail matter and letter moving means, substantially as described.
47. In an apparatus for distributing mail matter, the combination of several series of letter receptacles, several letter moving devices corresponding to said series of receptacles, respectively, a main letter-moving device adapted to convey but one letter at a time and deliver the same to any one of said first mentioned letter moving devices, means permitting said main letter moving device to move but a single stroke at each operation, and letter controlling devices, substantially as described.
48. In an apparatus for distributing mail matter, the combination of a series of letter receptacles having letter passages communicating therewith, a reciprocating main letter conveyer adapted to carry but one piece of mail matter at a stroke and to deliver the same into any one of said passages, and letter controlling means, substantially as described.
49. In an apparatus for distributing mail matter, the combination of series of letter receptacles having letter passages thereto, a main letter conveyer normally at rest and adapted to convey one piece of mail matter at a stroke to any one of said passages, and mechanism for moving said conveyer a single stroke at a time and returning the same to rest, substantially as described.
50. In an apparatus for distributing mail matter, the combination of letter moving devices arranged to receive individual pieces of mail matter and distribute the same individually to various points of delivery comprising a letter mover normally at rest, actuating mechanism therefor, devices to bring said mover to its normal position at rest on the completion of each stroke, and means for sorting the pieces of mail matter individually, substantially as described.
51. In a mail distributing apparatus, the combination of a series of letter boxes, a reciprocating letter mover movable back and forth above the boxes, means to cause delivery of a letter to any one of said boxes, and manually operated devices controlling said means, substantially as described.
52. In combination, in a mail distributing apparatus, mechanism to successively remove pieces of mail matter from a common pile and distribute the same to various predetermined points of delivery comprising a periodically movable initial feeder, driving means therefor, trip mechanism for throwing said feeder into and out of operative connection with said driving means, and series of manually operated controllers controlling said trip mechanism and determining the delivery point of each piece of mail matter, substantially as described.
53. In combination, in a mail distributing apparatus, driving means, letter moving devices having actuating means, a trip mechanism whereby the driving means is thrown into and out of operative relation with respect to said actuating means, letter controlling devices, and mechanisms controlling said letter controlling devices and said trip mechanism, substantially as described.
54. In a mail distributing apparatus, the combination of devices for moving and individually sorting pieces of mail matter, driving means, trip mechanism, whereby operative relation is established between said driving means and letter moving devices, and series of manually operated movable devices each representing a different delivery point for pieces of mail matter and controlling the sorting devices and said trip mechanism, substantially as described.
55. A mail distributing apparatus comprising a case of boxes, each box having a letter ingress opening into the top of the interior thereof and an end letter egress opening, and letter moving and controlling mechanisms, substantially as described.
56. A mail distributing apparatus comprising series of letter compartments, letter moving mechanisms arranged to move the letters successively from a common source and distribute the same to various predetermined compartments, and means delivering the letters flat face down in the compartments, substantially as described.
57. In a mail distributing apparatus, a row of letter compartments in combination with a letter holder or carrier moving over the compartments, and means for removing the letter therefrom and causing the same to drop into any compartment, substantially as described.
58. In a mail distributing machine, the combination of a series of receptacles, a series of controlling devices corresponding to and indicating said receptacles, and letter moving and directing mechanism controlled by said devices.
59. A mail distributing apparatus com-

prising letter conveying, moving and directing mechanisms constructed and arranged to take the individual pieces of mail matter from a common source and distribute them 5 to various predetermined points, and controlling means acting on said mechanisms to determine the particular point to which each piece of mail matter is delivered.

60. A mail distributing apparatus comprising 10 series of receptacles for the mail matter, each receptacle having an end opening for the removal of the letters deposited therein, and a letter ingress opening into the upper or top portion thereof, and means for distributing 15 the letters to the boxes and directing the same thereinto, substantially as described.

61. A mail distributing apparatus comprising 20 series of receptacles for receiving the mail matter, each receptacle having an opening through which the mail matter can be removed therefrom, and a letter ingress opening into the top portion thereof, in combination with letter conveying means moving 25 all the above said receptacles and from which the individual pieces of mail matter can drop into any receptacle through the ingress opening thereof, and devices determining the particular receptacle into which each 30 letter is to be dropped, substantially as described.

62. In combination, a letter feeder having a biting portion arranged to positively take hold of and feed a piece of mail matter, a feed stroke spring device for yieldingly moving 35 said feeder on its feeding stroke, and means for moving the feeder on its return stroke and against the tension of said spring device.

40 63. In combination, a letter feeder arranged to positively take hold of and successively feed pieces of mail matter, a feed stroke spring for actuating said feeder yieldingly on its feeding stroke, and feeder operating 45 connections for moving the feeder on its return stroke against the tension of said spring, comprising manually moved elements.

64. In a mail distributing apparatus, in 50 combination an initial feeder, and feeder operating connections comprising a series of key levers whereby the feeder is manually moved by the operative movement of the key levers.

55 65. A mail sorting device comprising a plurality of fixed letter receptacles, means for carrying individual letters separately and successively from a common source, and means for distributing the said letters into 60 the various predetermined fixed letter receptacles.

66. A mail sorting or distributing apparatus comprising series of boxes or receptacles having passages thereto, conveying 65 and letter controlling devices for carrying

the letters successively from a common source, and directing them separately to predetermined boxes, and series of controlling mechanisms corresponding to and indicating the various boxes and controlling said devices to pass each letter to a box indicated by the particular controlling mechanism actuated, substantially as described. 70

67. A mail sorting or distributing apparatus wherein the mixed letters are carried 75 from a common source and respectively distributed to the various boxes or receptacles in which they belong, comprising series of boxes or receptacles in which the letters are distributed, a general or main way, a conveyor receiving the letters successively from the common source, mechanism directing the letters to their proper boxes, and controlling and actuating mechanisms whereby each letter is deposited in a predetermined box, 80 substantially as described.

68. A mail sorting or distributing apparatus, wherein the letters are successively taken from a common source and distributed to various predetermined boxes or receptacles, comprising series of boxes or receptacles, series of controlling devices, such as key levers, corresponding to or indicating said boxes, respectively, letter conveying and directing mechanisms receiving the letters from said common source and directing the same individually to predetermined boxes, said directing mechanisms operatively connected to said controlling devices and controlled thereby to direct each letter 100 to the box indicated by the particular controlling device moved by the operator, substantially as described.

69. A mail sorting or distributing apparatus comprising a support for the common 105 pile of mixed letters, letter moving and distributing mechanism, and manually operated controlling means therefor, substantially as described.

70. In an apparatus for distributing individual pieces of mail matter from a common source into predetermined boxes of series, series or a case of boxes or receptacles having letter passages to the boxes, and a main letter way communicating with all said passages and arranged to pass a letter into any passage, substantially as described. 115

71. In an apparatus of the character described, series of boxes, series of controlling devices corresponding to and indicating the 120 boxes, respectively, and letter moving and directing mechanisms controlled by said devices, substantially as described.

72. In an apparatus of the character described, a case of letter boxes or receptacles 125 having a series of letter passages communicating with the boxes, and letter moving and directing, and controlling mechanisms, for delivering each letter into a predetermined passage, substantially as described. 130

73. In an apparatus of the character described, a case or series of boxes or receptacles for mail matter, series of openings to said boxes, and means for feeding letters into any one of said openings, and controlling mechanism to cause discharge of each letter into any predetermined opening.

74. In an apparatus of the character described, a case or series of boxes having letter receiving openings thereto, in combination with a main letter conveyer arranged to discharge letters thereto, substantially as described.

75. In an apparatus of the character described, a case or series of boxes or receptacles, each box having a side ingress opening for a piece of mail matter and an open end for egress of the pile of mail matter in the box, and moving or conveying means for directing pieces of mail matter through said side openings into the boxes, substantially as described.

76. In an apparatus of the character described, a case or series of boxes or receptacles, in combination with letter conveying and directing mechanisms, constructed and arranged to receive individual pieces of mail matter from a common source and deliver the same individually in predetermined boxes, substantially as described.

77. In an apparatus of the character described, a case or series of boxes having side openings, mechanism for depositing letters in said boxes through said openings, and controlling means acting on said mechanism and thereby determining the particular box in which each piece of mail matter is deposited, substantially as described.

78. In a mail distributing apparatus, boxes or receptacles arranged in several series, letter passages for each series of boxes, each box opening into the passage of its series, means to direct a letter in a passage into any particular box of the series, and means discharging letters individually into any particular passage, substantially as described.

79. A mail distributing apparatus comprising letter moving and directing mechanisms constructed and arranged to take the individual pieces of mail matter from a common source and distribute them to various predetermined points, and controlling means acting on said mechanisms to determine the particular point to which each piece of mail matter is delivered, substantially as described.

80. A mail distributing apparatus comprising letter moving and directing mechanisms, constructed and arranged to take the pieces of mail matter individually from a common source and deposit them individually at various points, and series of controlling devices for the said mechanisms determining the particular delivery point of each piece of mail matter, substantially as described.

81. The combination with letter moving devices and means for individually sorting the mail matter, of a case or series of boxes having letter passages opening thereto, substantially as described.

82. The combination with a case or series of boxes having letter openings thereto, of a main letter way or conveyer common to all of said openings, and means for individually distributing the pieces of mail matter, substantially as described.

83. In combination, series of boxes or receptacles, letter moving means, and series of independent gates, deflectors, or strippers controlling the letters and directing each individual letter on its particular course, substantially as described.

84. In combination, series of boxes or receptacles, each indicating a particular route or destination for mail matter, letter moving means, and independent letter controlling means controlling and directing each individual piece of mail matter to a desired box.

85. An apparatus for receiving letters from a common source and individually delivering them at various predetermined points comprising letter ways, letter conveyers, independent letter directing gates, and independent controlling devices for operating the gates to determine the delivery point of each letter, in combination.

86. In combination, letter moving devices, controlling mechanisms, said devices and mechanisms constructed and arranged to successively take individual pieces of mail matter from a common source, and distribute the same to various points or locations, and a series of key levers, indicating the various points of distribution, each acting on said mechanisms and predetermined the destination of each piece of mail matter, substantially as described.

87. In a mail distributor, the combination of driving means, letter moving and directing mechanisms, arranged to take the letters successively from a common source and distribute the same to various boxes or receptacles, and series of key levers, said levers controlling certain of said mechanisms and determining the particular boxes to which the respective pieces of mail matter are guided or directed.

88. In a mail distributor, letter moving devices, receiving the mixed letters from a common source, in combination with a main letter way provided with branch letter passages, boxes or receptacles opening into certain passages, and controlling mechanisms determining the passage which each letter will enter from said way.

89. In combination, in a mail distributing apparatus, letter conveying apparatus arranged to receive the letters successively from a common source and deliver the same at various locations, series of letter directing

means, and series of controlling devices for said means, whereby said means are controlled to deliver the letters at various predetermined locations.

5 90. In combination, in a mail distributing apparatus, series of separate letter depositories, a letter conveyer receiving the letters successively from a common source and delivering the same successively at various 10 points, and series of independent controlling devices, whereby each letter is separately delivered to a predetermined depository.

15 91. In a mail distributor, the combination of series of letter depositories, letter conveying devices, and series of controlling devices each corresponding to and indicating a particular letter repository, whereby the letters are moved and controlled and delivered separately to predetermined letter depositories.

20 92. A mail distributing apparatus comprising letter conveying and moving mechanisms carrying the letters from a common source and delivering the same to various 25 points, and sorting or distributing controlling mechanisms, whereby the letters are individually sorted and delivered at various predetermined points.

25 93. In a mail distributor, series of separate letter depositories, in combination with letter sorting, moving and controlling mechanisms individually sorting and delivering the letters into said depositories from a common source.

30 94. In a mail distributor, the combination of series of letter boxes having letter openings, a letter conveyer common to all of said openings and arranged to discharge letters into any one of them, and sorting and controlling means sorting and determining the particular opening into which each letter shall be discharged.

35 95. In combination, in a mail distributor, series of letter boxes having passages thereto, a letter way common to the upper ends of all said passages, fingered gates normally closing said passages and forming the floor of said way, mechanism to move the letters successively along said letter way, and controlling means for said gates, substantially as described.

40 96. A series of boxes having a main letter way above the same, in combination with letter moving and distributing mechanism individually sorting the pieces of mail matter.

45 97. A series of boxes having a main letter way with the floor thereof extended at one end, and provided with a holder for a pile of letters, letter conveying devices, and letter directing mechanisms, whereby the letters from said pile are individually sorted into various boxes.

50 98. A series of boxes, letter passages communicating with the boxes, a main letter

way communicating with the passages, and gates between the passages and way.

55 99. In combination, series of boxes, letter passages communicating therewith, gates normally closing certain boxes and arranged to direct letters thereinto when opened, a letter conveyer arranged to discharge each letter into any particular passage, and controlling means.

60 100. A series of letter receiving receptacles, letter passages communicating therewith, gates at the receiving ends of the passages, and a letter mover or conveyer common to all said passages and so formed that any gate can move through the path of movement thereof and deflect the letter therefrom into the particular passage.

65 101. In combination, in a mail distributor, series of boxes, each series having its own letter passage, means in each passage to direct a letter into any particular box, and prevent entrance of the same into other boxes, mechanisms for delivering each letter into a particular passage and prevent entrance thereof into other passages, and controlling devices.

70 102. In a machine of the character described, series of boxes, letter moving means receiving the letters, directing devices arranged to deliver each letter into any particular box, and series of key levers, corresponding to said boxes and controlling said letter directing devices to determine the box to which each letter is delivered.

75 103. In an apparatus of the character described, series of boxes or receptacles, passages thereto, movable letter forcing means in the passages, each box having a receiving opening, and movable mechanisms arranged to direct any letter into any particular box.

80 104. In an apparatus of the character described, a series of letter boxes or receptacles, letter passages communicating therewith, each box having a receiving opening, and letter directing means arranged at said opening.

85 105. In an apparatus of the character described, a series of boxes, a letter passage beside the same and opening into all the boxes, fingered gates for the boxes arranged in the passages, and letter moving belts arranged longitudinally of the passages and alternating with the fingers of the gates.

90 106. In combination, series of boxes having a passage communicating therewith, and letter forcing belts longitudinally of the passage.

100 107. A mail distributing apparatus having series of letter boxes having side openings and means for forcing letters thereto.

105 108. In combination, a mail distributor, several series of boxes, letter passages for the series, respectively, each passage opening into boxes of its series, letter forcing belts in

each passage, driving means, all the belts connected with the driving means and actuated longitudinally of the passages.

109. In an apparatus of the character described, series of boxes for the letters, letter moving or conveying means, letter directing means to deliver each letter into a predetermined box, series of key levers arranged at the front of the machine and connected with 10 and controlling said directing means.

110. In an apparatus of the character described, series of boxes, series of letter controlling guides or gates, series of crank shafts having connections to various gates, and 15 series of controllers, certain controllers connected to actuate certain crank shafts.

111. In an apparatus of the character described, letter conveying mechanisms, driving means, series of boxes, series of letter directing gates or guides, and series of key levers, certain of said key levers connected to 20 actuate certain of said gates.

112. The combination of series of slides or plates, series of separate manually operated 25 devices, each connected to operate a slide, so that each device operates a particular slide, boxes, series of letter directing means, certain slides controlling and actuating certain letter directing means.

113. In combination, in a mail distributor, a crank shaft, a slide arranged to rock the 30 crank shaft, a key lever pivoted to the slide, and letter distributing mechanism having a letter directing device controlled by said shaft.

114. In combination, in a mail distributor, series of mail repositories, a series of manually operated slides corresponding thereto, letter directing means, each slide controlling 40 a means to direct the letter to a particular repository, and letter conveying mechanism.

115. In combination, in a mail distributor, series of letter directing means, a series of 45 rock shafts, each rock shaft controlling certain letter directing means, and series of keys, each key arranged to rock a certain shaft or shafts.

116. In a mail distributor, the combination of a series of rock shafts having cranks, a 50 series of letter repositories, series of letter directing means controlled by said cranks, a series of manually operated slides, said slides having means to engage and rock certain shafts to move certain directing means, and 55 move independently of the remaining shafts.

117. In combination, a letter distributing mechanism having letter guiding means, a series of crank shafts, controlling said means, each having a forwardly extending flange or 60 plate, the series of slides arranged loosely in openings in the plates, said slides having projections to strike certain plates only, and means for longitudinally moving the slides.

118. The combination with a vertical row

of mail boxes, each provided with an opening 65 for the entrance of the mail, of a passage extending along the sides of said boxes containing said openings, and switches arranged opposite said openings and adapted to extend across the chute for intercepting the 70 mail delivered into the same.

119. In combination, in a mail distributing apparatus, series of letter boxes, series of letter directing gates, means for moving the letters over said gates, and means for 75 moving any gate to intercept the letter.

120. In combination, in a mail distributing apparatus, series of letter boxes, series or rows of fingered letter directing gates, means for moving the letters successively along said 80 rows, and means for moving any gate to intercept the letter and deflect the same from said means.

121. In combination, in a mail distributing apparatus, a row of letter boxes having 85 letter receiving openings, a letter conveyer receiving the letters from a common source and arranged to deliver them individually into any box, and controlling devices determining the particular box into which each 90 letter is delivered.

122. In combination, in a mail distributing apparatus, a row of letter boxes having letter receiving openings, a series of swinging 95 gates closing said openings, means to move the letters past said gates, and mechanism to swing any gate outwardly to deflect the letter into its box.

123. In combination, in a mail distributing apparatus, letter moving mechanism arranged to move the letters successively from 100 a common source and distribute and deliver the same individually to various predetermined points, series of letter directing gates each comprising a series of fingers arranged 105 to intercept the letter and swing across the plane of the letter moving mechanism, and gate controlling means.

124. In combination, in a mail distributing apparatus, mechanism for moving the 110 letters from a common source and delivering the same to various predetermined points comprising a series of parallel separated belts, series of gates having fingers alternating with the belts and arranged to move out 115 between them to intercept a letter and deflect the same laterally therefrom, and controlling mechanisms.

125. In combination, in a mail distributing apparatus, series of letter boxes having 120 letter receiving openings, a row of normally closed swinging gates overlapping or breaking joints with each other, mechanism to swing any gate outwardly to intercept a letter and deflect the same laterally, and letter 125 moving means arranged to move the letters successively along said row of gates.

126. In combination, in a mail distribut-

ing apparatus, series of letter boxes having letter receiving openings, a main letter way communicating with all of said openings, and extended at one end, a support for the 5 common pile of letters at said end, letter moving means movable along said way from said extended end, controlling mechanisms determining the box to which each letter is to be delivered, and manually operated ac- 10 tuating means for said controlling mechanisms arranged adjacent to said support for the common pile of letters.

127. In combination, in a mail distributing apparatus, series of letter boxes, having 15 letter receiving openings, a main letter conveyer arranged to take the letters from a common source and deliver the same at various predetermined points, controlling means determining the delivery point of 20 each letter, series of manually operated actuating devices for said controlling means and corresponding to the series of boxes, respectively, and arranged adjacent to said common source from which said conveyer re- 25 ceives the letters.

128. In combination, in a mail distributing apparatus, series of letter boxes arranged in rows with letter passages beside the rows, respectively, letter conveying 30 means movable longitudinally in each passage, gates arranged to intercept the letters therein, and deflect the same into any box, means to deliver the letters to any passage, and controlling mechanisms predetermining 35 the particular box into which any letter is to be delivered.

129. In combination, in a mail distributing apparatus, a row of boxes having openings, a row of swinging gates, each gate 40 mounted at a box opening to close the same or swing outwardly therefrom, means to move a letter along said gates so that any gate can intercept the same and deflect the letter into its box, and controlling mech- 45 anisms.

130. In combination, in a mail distributing apparatus, series of letter boxes, a series of letter passages, a series of swinging gates normally closing the same, mechanism for 50 moving the letters successively past said gates, whereby any gate can swing out and intercept a letter and deflect the same into its passage, and controlling mechanisms.

131. In combination, in a mail distributing apparatus, series of letter boxes, letter moving devices, letter directing gates, series of manually operated actuating mechanisms corresponding to and indicating the boxes, respectively, and operatively connected with 60 and controlling said gates.

132. In combination, in a mail distributing apparatus, series of letter boxes, letter moving mechanisms, controlling devices determining the particular box to which each 65 letter is to be delivered, series of manually

operated actuating means for said controlling devices corresponding to and indicating said boxes, respectively.

133. In combination, in a mail distributing apparatus, letter conveying devices ar- 70 ranged to receive the letters from a common source and deliver the same at various pre- determined points, means controlling the points at which the letters are individually delivered, and series of operating devices op- 75 eratively connected with said controlling means, and respectively corresponding to and indicating the various points of delivery for the letters, whereby the point of delivery of a letter is predetermined by the operation 80 of the operating device corresponding to and indicating such point.

134. In combination, in a mail distributing apparatus, series of letter boxes, letter conveying devices, letter directing and con- 85 trolling means determining the box to which each letter is delivered, a series of shafts op- eratively connected with and actuating said controlling means, series of slides acting on and actuating said shafts, and series of oper- 90 ating devices for said slides indicating and corresponding to said boxes, respectively.

135. In a mail distributing apparatus, letter conveying devices and controlling means, whereby the letters are moved from a com- 95 mon source and delivered at various pre- determined points, in combination with a series of separate movable operating members corresponding to and indicating said points to which the letters are delivered, respec- 100 tively, and actuating connections moved by said operating devices and governing said controlling means, respectively, to determine the particular point of delivery of each letter.

136. In combination, in a mail distribut- 105 ing apparatus, series of letter boxes, letter conveying devices, letter directing gates, se- ries of independent operating rock shafts op- eratively connected with said gates so that certain shafts control certain gates, and se- 110 ries of independent movable operating mem- bers corresponding to and indicating said boxes, respectively, certain members oper- atively connected to rock certain rock shafts.

137. In combination, in a mail distribut- 115 ing apparatus, letter conveying means, ar- ranged to deliver the letters at various pre- determined points, movable letter directing means determining the delivery points of the letters, series of independently movable man- 120 ually operated spring held members, a corre- sponding series of independent slides oper- atively confined to said members, respec- tively, and a series of rock shafts, operatively connected with and actuating said letter di- 125 recting means, certain slides operatively ar- ranged to rock certain shafts so that certain letter directing means are operated by cer- tain of said manually operated members.

138. In combination, in a mail distribut- 130

ing apparatus, a frame, series of letter boxes, letter conveying means, series of letter deflecting gates, series of manually operated levers carried by the frame adjacent to the initial letter receiving point of said conveying means, and series of controlling connections operatively arranged between said levers and said gates, certain levers operatively controlling several gates, and other levers operatively controlling only one gate.

139. In combination, in a mail distributing apparatus, a frame, a series of letter boxes arranged therein, letter conveying means, controlling means determining the particular box to which each letter is delivered, series of manually operated spring pressed levers arranged at one end of and carried by said frame and corresponding to and indicating said boxes, respectively, and operative connections between said levers and said controlling means arranged and constructed so that the operation of any lever will cause the delivery of the letter to the box indicated by such lever.

140. In combination, in a mail distributing apparatus, series of boxes, a frame, a main letter way, a support at one end of the way for a pile of letters, a letter conveyer movable along said way from a point adjacent to said support, letter directing gates, series of vertically movable key levers arranged at one end of the frame below said support, and operative connecting devices between said levers and said gates.

141. In a mail distributing apparatus, in combination a case of letter boxes, having letter passages thereto, letter moving mechanisms, swinging gates controlling the entrance of letters into the passage, swinging gates for the boxes, respectively, all of said gates having end operating cranks, a frame, a series of rock shafts having cranks with pull connections to said gate cranks, a separate rock shaft being provided for each passage gate, and a rock shaft for each series of box gates, and series of manually operated movable members corresponding to and indicating the various boxes and having operative connections with said rock shafts, certain of said members operating several rock shafts each, and certain operating only one rock shaft each.

142. In a mail distributing apparatus, in combination, a series of vertical rows of letter boxes having side openings, each row having a vertical letter passage, letter moving means to deliver letters into any passage, movable letter directing gates for all of said passages excepting the last passage, movable letter directing gates for all of the boxes excepting the bottom boxes, and gate operating mechanisms.

143. In a mail distributing apparatus, manually operated actuating devices, and

letter controlling means controlled by said devices, in combination with a lock for said actuating devices.

144. In a mail distributing apparatus, the combination of letter moving means, letter controlling devices, a series of movable manually operated mechanisms operatively actuating or setting said controlling devices, and locking mechanism for holding a controlling device in its set position until another manually operated mechanism is moved to set another controlling device.

145. In a mail distributing apparatus, the combination of series of vertically movable levers, a locking device arranged to hold any lever depressed, said levers constructed and arranged to operate said lock to release a lever held thereby on depression of another lever, and letter controlling and moving means.

146. An apparatus for distributing mail matter comprising means for supporting pieces of mail matter at a common source, and mechanism for receiving the pieces of mail matter from the common source and sorting or distributing the same and delivering the pieces of mail matter at various predetermined points of delivery.

147. An apparatus for distributing mail matter comprising series of receptacles, manually controlled mail matter directing means, and mechanisms individually receiving the pieces of mail matter and sorting and distributing the same to predetermined receptacles.

148. In an apparatus for distributing mail matter, the combination of series of receptacles, devices for conveying individual pieces of matter, and devices operated independently of the movement of the matter for individually sorting the pieces of mail matter and insuring the delivery thereof to predetermined receptacles.

149. In an apparatus for distributing mail matter, mechanisms to receive the pieces of mail matter at a common source and distribute the same individually to various predetermined points of delivery comprising friction letter conveying belts.

150. An apparatus for distributing mail matter, wherein the individual pieces are received from a common source and delivered at various predetermined points of delivery comprising letter conveying means, movable devices controlling the delivery point of the individual pieces, and controlling means for said movable devices constructed and arranged to return each movable device to its normal position on the operative stroke of a controlling device.

151. In combination, in a mail distributing apparatus, means receiving the individual pieces of mail matter from a common source and delivering the same at various points of

delivery, movable devices controlling the delivery points of the individual pieces, manually operated controlling mechanisms for said devices whereby the movement of a controlling mechanism will set a movable device or devices to cause delivery of an individual piece at a certain point, and means to hold a device set when its mechanism is moved and permit return thereof to its normal position on movement of another mechanism.

152. A mail distributing apparatus comprising letter boxes having letter receiving openings, a letter mover common to all of said boxes, and separate manually operated controlling means whereby a letter from said mover can be delivered to any box.

153. A mail distributing apparatus comprising letter boxes, a letter conveyer movable above said boxes, means determining the particular box to which a letter from said conveyer is delivered, and manually operated controlling devices for and corresponding to said means.

154. A mail distributing apparatus comprising a row of letter receptacles having letter receiving openings, a letter conveyer arranged to deliver letters to any of said openings, and means independent of the passage of the letters controlling the delivery points of the letters.

155. A mail distributing apparatus comprising a series of letter receptacles, a letter conveyer, means controlling the delivery of letters from said conveyer to any one of said receptacles, and manually operated controllers controlling said means.

156. A series of letter boxes having a passage communicating therewith, a letter forcing belt arranged longitudinally of the passage, and means coöperating with the belt and determining the particular box to which each letter shall be delivered.

157. The combination of series of slides, series of manually operated elements each connected to operate a slide, whereby each operates a particular slide, letter receptacles, series of letter controlling devices, certain

slides controlling certain letter controlling devices.

158. In combination, a series of letter boxes, and letter moving and controlling devices comprising series of manually operated movable elements, whereby each letter can be delivered into any one of said boxes.

159. In combination, a plurality of letter receptacles, a letter mover arranged above the same, means causing delivery of each letter from said mover to any one of said receptacles, and manually operated movable elements controlling said means.

160. In combination, in a mail distributing machine, letter moving and controlling devices for removing the pieces of mail matter successively from a common source and distributing the same to various predetermined points of delivery, and a case of boxes.

161. A mail distributing apparatus wherein the letters are conveyed from a common source and distributed to various predetermined boxes, a case of letter receptacles wherein the receptacles are arranged in series, letter conveying means common to all the series of receptacles and along and common to the receptacles of each series, whereby each letter can be delivered to any series and then delivered to any receptacle of such series, letter directing means, and controlling devices therefor.

162. In a mail distributing machine, the combination of a series of receptacles, a series of controlling devices corresponding to and indicating said receptacles, and letter moving and directing mechanisms controlled by said devices, said letter moving mechanism comprising and including a letter-moving marking device operating to positively move and advance each letter on its course.

In testimony whereof I affix my signature, in presence of two witnesses.

WILLIAM BARRY.
